UNITED STATES PATENT OFFICE.

CHARLES H. IRWIN, FRIEDERICH MILL, AND JOHN E. HITCH, OF WILMING-
TON, OHIO; SAID MILL AND HITCH ASSIGNEES TO SAID IRWIN.

BORING-MACHINE.

SPECIFICATION forming part of Letters Patent No. 427,325, dated May 6, 1890.

Application filed December 28, 1889. Serial No. 335,218. (No model.)

To all whom it may concern:

Be it known that we, CHARLES H. IRWIN, FRIEDERICH MILL, and JOHN E. HITCH, all of 5 Wilmington, in the county of Clinton and State of Ohio, have invented a new and Improved Boring-Machine, of which the following is a full, clear, and exact description.

The object of the invention is to provide a new and improved boring-machine which is 10 simple and durable in construction, very effective in operation, and permits of quickly changing the speed, so as to run the machine slow when a large auger is used and to run it fast when a small auger is used.

15 The invention consists of a shaft mounted to be shifted and carrying two gear-wheels and a second shaft carrying two gear-wheels adapted to be thrown alternately in contact with the said first-named gear-wheels by 20 shifting one of the said shafts, so as to change the speed of the machine.

The invention also consists of certain parts and details and combinations of the same, as 25 will be hereinafter fully described, and then pointed out in the claims.

Reference is to be had to the accompanying drawings, forming a part of this specification, in which similar letters of reference indicate corresponding parts in all the figures.

30 Figure 1 is a front view of the improvement with parts of the frame broken out. Fig. 2 is a side elevation of the same. Fig. 3 is an enlarged sectional plan view of the improvement on the line $x-x$ of Fig. 1. Fig. 4 is a side elevation of a locking-latch for the shaft. Fig. 5 is an enlarged sectional front view of part of the improvement on the line $y-y$ of Fig. 2. Fig. 6 is an enlarged plan view of one of the gear-wheels. Fig. 7 is a face 40 view of one of the clutch gear-wheels. Fig. 8 is an enlarged sectional side elevation of a modified form of part of the improvement. Fig. 9 is a front view of one of the clutch-wheels for the said modified form, and Fig. 45 10 is a side elevation of the locking-latch for one of the shafts.

The improved boring-machine is provided with a suitably-constructed base A, on which are secured the standards B B, supporting a bolt C, on which is mounted to turn a sleeve

D, provided with the notched disks D' D', adapted to engage with their notches corresponding notches in the disks B' B', formed on the standards B B. The disks D' D' support posts E E, connected with each other by suitable cross-bars E', so as to form a frame which can be swung in any desired angle by loosening the nut C' of the bolt C, so that the notched disks D' can pass the notches in the disks B' until the desired inclined position 55 of the frame is reached. When the desired position is obtained, the nut C' is again screwed up, so as to draw the notched disks B' on the standards B B firmly into the notches of the disks D', thus locking the latter in place to hold the posts E in the desired inclined position.

On the front of the posts E is held to slide up and down a frame F, provided with guiding-lugs F', engaging guiding-grooves E², 70 formed on the said posts E'. (See Fig. 3.) The frame F is provided with the bearings F' and F², in which is mounted to turn the horizontally-extending shaft G, also adapted to slide in the said bearings in order to change the 75 speed of the machine, as hereinafter more fully described.

On the ends of the shaft G are secured the crank-arms G' and G², preferably arranged to extend in opposite directions, as is plainly 80 shown in Fig. 1. When the shaft G has been shifted into the desired position to the right or left, the shaft is locked in place to prevent a displacement, but to permit of turning it by means of latches H and H', pivoted on the 85 bearings F' and F², respectively, and adapted to be thrown between the hub of the crank-arms G' and G² and the outer ends of the bearings F' and F², respectively. When one of the latches is disengaged from the shaft, 90 then the other is adapted to engage the shaft, and vice versa.

As shown in Fig. 1, the latch H' is disengaged and the shaft G is shifted into its position to the left, the latch H engaging the 95 shaft between the hub of the handle G' and the bearing F', thus preventing the shifting of the shaft G to the right. When the latch H is thrown out of contact with the shaft G, the latter can be shifted to the right, and then 100

the latch H' thrown in gear with the shaft G to prevent the movement of the latter to the left.

On the shaft G, near its middle, is secured a bevel gear-wheel I, adapted to mesh into a bevel gear-wheel J when the shaft G is in its left-hand position, as shown in Figs. 1 and 5. The gear-wheel J is fastened on the upper end of the shaft K, mounted to turn in a bearing F³ of the frame F, and carrying at its lower end a chuck L, supporting the auger N, preferably of the construction shown and described in Letters Patent numbered 306,907, granted to Charles H. Irwin October 21, 1884.

15 On the face of the bevel gear-wheel I are formed clutch-teeth I', adapted to engage similar clutch-teeth N', formed on one face of the bevel gear-wheel N, mounted to turn loosely on the shaft G between the bevel gear-wheel I and the bearing F². The loose bevel gear-wheel N is always in mesh with a large bevel gear-wheel O, formed integral with the bevel gear-wheel J, so as to turn with the latter the shaft K.

25 When the machine is in the position shown in Figs. 1, 2, 3, and 5 and the shaft G is revolved by the operator turning the crank-arms G' and G², then the small bevel gear-wheel I, meshing into the small bevel gear-wheel J, turns the shaft K at a high rate of speed to drill small holes with augers of small diameter. Now when the operator desires to use a large auger the speed of the machine must necessarily be reduced. For this purpose the 35 latch H is disengaged from the shaft G, the latter is shifted to the right, and the latch H' is placed into contact with the shaft G to lock the latter in its right-hand position. The shifting of the shaft G from the left to the 40 right moves the clutch-teeth of the gear-wheel I' into engagement of the clutch-teeth N' of the smaller gear-wheel N, so that when the shaft is now rotated the gear-wheel N rotates with the said shaft, as it is coupled to the 45 gear-wheel I. The latter, by shifting the shaft G to the right, is disengaged from the smaller bevel gear-wheel J, and now on turning the shaft G its motion is transmitted by means of the gear-wheel N to the large bevel gear-wheel O, secured on the shaft K, which is thus turned at a low rate of speed. Thus by 50 simply shifting the shaft G a fast or a slow motion can be given to the shaft K during the same number of revolutions imparted to 55 the shaft G. When the aperture is bored by the auger N and the operator desires to withdraw the auger, the following device is used to quickly raise the frame F to move the auger out of the aperture: On the bevel gear-wheel N is formed a spur-wheel N², adapted to be engaged by a rack P, mounted to slide on one of the posts E, so as to engage and disengage the said spur-wheel N² whenever desired. The rack P is provided near its upper 60 end with an inclined slot P', engaging a bolt Q, held on the respective post E. On the lower end a similar arrangement may be made,

or a pin P² may be secured to the rack P to engage the slot E⁴, formed in the respective post E and inclined similarly to the slot P'. On the extreme lower end of the rack P is arranged a forwardly-inclined arm P³, passing through a keeper R and provided with a hook P⁴, adapted to engage the top of the keeper R when the rack P is moved upward, 75 so as to slide rearward out of contact with the spur-wheel N², and then the hook P⁴ rests on top of the keeper R and locks the rack P in position—that is, out of contact with the spur-wheel N². When the operator desires to move 80 the frame F upward after the hole is drilled, the rack P is swung downward and outward by the operator disengaging the hook P⁴ from the keeper R and permitting the rack to slide downward and outward in mesh with the 85 spur-wheel N². The operator then, turning the shaft G in the reverse direction, causes the said spur-wheel N² to travel upward on the rack P, thus raising the frame and shifting the auger N out of the drill-hole. 90

It will be seen that in order to change the machine from a slow to a fast motion, or vice versa, it is necessary to shift one of the shafts. This can also be accomplished as shown in Figs. 8, 9, and 10, in which the shaft G is 95 mounted to turn, but not to slide, and the bevel gear-wheel N is formed integral with the gear-wheel I, secured on the shaft G. The bevel gear-wheel J is not formed integral with the gear-wheel O, but is provided with 100 clutch-teeth J², adapted to engage corresponding clutch-teeth O', formed in the face of the gear-wheel O. The latter is mounted to turn loosely on the hub of the gear-wheel J, while said gear-wheel J is fastened on the shaft K 105 and rests on the sleeve J', held to slide vertically in the bearing F³. A pin S' projects from the sleeve J' through a slot F⁴ in the bearing F³, and this pin is adapted to be locked in an uppermost position by a latch 110 S, so as to hold the sleeve J' in an uppermost position and the gear-wheel J in mesh with the gear-wheel I. The gear-wheels J and O are thus disconnected, and the gear-wheel O rotates loosely when the shaft G is turned. 115 A fast motion is thus imparted to the shaft K, as the motion of the shaft G is transmitted by the gear-wheel I to the gear-wheel J on the said shaft K. When the latch S is thrown over the pin S', the sleeve J' and the 120 gear-wheel J are permitted to slide downward, so that the clutch-teeth J² engage the clutch-teeth O' of the gear-wheel O, at the same time disengaging the gear-wheel J from the gear-wheel I. Motion is now transmitted 125 from the gear-wheel N to the gear-wheel O, which, being locked to the gear-wheel J, imparts a slow motion to the shaft K. This construction is similar to the one above described and is for the same purpose. Thus it will be 130 seen that by a simple movement the speed of the machine can be quickly changed according to the size of the gear used, and the auger can be quickly withdrawn from the hole.

Having thus fully described our invention, we claim as new and desire to secure by Letters Patent—

1. In a boring-machine, the combination, 5 with a shaft mounted to turn and to be shifted lengthwise and two gear-wheels, of which one is fastened and the other is loose on the shaft, of a second shaft mounted to turn and carrying two integral gear-wheels adapted to 10 engage the said fast and loose gear-wheels, substantially as shown and described. 60
2. In a boring-machine, the combination, 15 with a shaft mounted to turn and to be shifted lengthwise and two gear-wheels, of which one is fastened and the other is loose, of a second shaft mounted to turn and carrying two integral gear-wheels adapted to engage the said fast and loose gear-wheels, and means, substantially as described, for locking the shaft 20 to be shifted in position, permitting it, however, to turn, substantially as shown and described. 70
3. In a boring-machine, the combination, 25 with posts, of a frame mounted to slide on the said posts, a shaft held to turn and adapted to be shifted in the said frame, a bevel gear-wheel having clutch-teeth secured on the said shaft, a second bevel gear-wheel held loose on the said shaft and adapted to be engaged 30 by the said first-named bevel gear-wheel, two integral gear-wheels of different diameter and adapted to mesh in the said gear-wheels on the said shaft, and a second shaft held at right angles to the said first-named shaft and carrying the said two integral gear-wheels, substantially as shown and described. 80
4. In a boring-machine, the combination, 35 with posts, of a frame mounted to slide on the said posts, a shaft held to turn and adapted to be shifted in the said frame, a bevel gear-wheel having clutch-teeth and secured on the said shaft, a second bevel gear-wheel held loose on the said shaft and adapted to be engaged by the said first-named bevel gear-wheel, two integral gear-wheels of different 40 diameter and adapted to mesh in the said gear-wheels on the said shaft, a second shaft held at right angles to the said first-named shaft and carrying the said two integral gear-wheels, substantially as shown and described. 90
5. In a boring-machine, the combination, 45 with posts, of a frame mounted to slide on the said posts, a shaft held to turn and adapted to be shifted in the said frame, a bevel gear-wheel having clutch-teeth and secured on the said shaft, a second bevel gear-wheel held loose on the said shaft and adapted to be engaged by the said first-named bevel gear-wheel, two integral gear-wheels of different 50 diameter and adapted to mesh in the said gear-wheels on the said shaft, a second shaft held at right angles to the said first-named shaft and carrying the said two integral gear-wheels, and a chuck held on the said last-named shaft for carrying the auger, substantially as shown and described. 100
6. In a boring-machine, the combination, 55 with posts, of a frame mounted to slide on the said posts, a shaft held to turn and adapted to be shifted in the said frame, a bevel gear-wheel having clutch-teeth and secured on the said shaft, a second bevel gear-wheel held loose on the said shaft and adapted to be engaged by the said first-named bevel gear-wheel, two integral gear-wheels of different diameter and adapted to mesh in the said gear-wheels on the said shaft, a second shaft held at right angles to the said first-named shaft and carrying the said two integral gear-wheels, and latches for alternately locking the first-named shaft in the right or left hand position, permitting the shaft, however, to turn in its bearings on the frame, substantially as shown and described. 75
7. In a boring-machine, the combination, 60 with posts, of a frame mounted to slide on the said posts, a shaft held to turn and adapted to be shifted in the said frame, a bevel gear-wheel having clutch-teeth and secured on the said shaft, a second bevel gear-wheel held loose on the said shaft and adapted to be engaged by the said first-named bevel gear-wheel, two integral gear-wheels of different diameter and adapted to mesh in the said gear-wheels on the said shaft, a second shaft held at right angles to the said first-named shaft and carrying the said two integral gear-wheels, and means, substantially as described, for locking the said posts in any desired position, as set forth. 85
8. In a boring-machine, the combination, 65 with posts, of a frame mounted to slide on the said posts, a shaft held to turn and adapted to be shifted in the said frame, a bevel gear-wheel having clutch-teeth and secured on the said shaft, a second bevel gear-wheel held loose on the said shaft and adapted to be engaged by the said first-named bevel gear-wheel, two integral gear-wheels of different 70 diameter and adapted to mesh in the said gear-wheels on the said shaft, a second shaft held at right angles to the said first-named shaft and carrying the said two integral gear-wheels, and means, substantially as described, for quickly raising the said frame on the said posts to withdraw the auger from the drilled hole, substantially as shown and described. 90
